UNITED STATES PATENT OFFICE

101,395

DESIGN FOR A BOAT OR SIMILAR ARTICLE

Alexander M. Peabody, Seattle, Wash., assignor to The Puget Sound Navigation Company,
Seattle, Wash., a corporation of Nevada.

Application March 24, 1936, Serial No. 61,771

Term of patent 14 years

To all whom it may concern:

Be it known that I, Alexander M. Peabody, a citizen of the United States, residing at Seattle, King County, Washington, have invented a new, original, and ornamental Design for a Boat or Similar Article, of which the following is a specification, reference being had to the accompanying drawing, forming part thereof, wherein—

Fig. 1 is a side view of a boat or similar article embodying the present design.

Fig. 2 is a plan.

Fig. 3 is a front end view of a boat or similar article embodying the present design.

I claim:

The ornamental design for a boat or similar article, as shown.

ALEXANDER M. PEABODY.
